B. W. KADEL

DRAFT RIGGING

Filed Sept. 2, 1922

INVENTOR
Byers W. Russell
BY
Ernest F. W. Bell
ATTORNEY

UNITED STATES PATENT OFFICE.

BYERS W. KADEL, OF BALTIMORE, MARYLAND, ASSIGNOR TO THE T. H. SYMINGTON COMPANY, OF NEW YORK, N. Y., A CORPORATION OF DELAWARE.

DEAFT RIGGING.

Application filed September 2, 1922. Serial No. 565,947.

To all whom it may concern:

Be it known that I, BYERS W. KADEL, a citizen of the United States, residing at Baltimore, State of Maryland, have invented certain new and useful Improvements in Draft Rigging; and I do hereby declare the following to be a full, clear, and exact description of the invention, such as will enable others skilled in the art to which it appertains to make and use the same.

My invention relates to draft rigging for railway cars and, generally stated, involves the production of a simple, strong, easily manufactured and useful yoke member provided with means for receiving and retaining the cushioning element of the draft gear in encased relation to the associated draft rigging parts.

The principal feature of my invention, particularly stated, resides in the provision of friction draft rigging including a yoke member formed with a housing, arranged to receive the cushioning element of the draft rigging through the front of the yoke.

Another feature of my invention is to provide a combined integral yoke member and draft gear housing, said yoke member having a hooded end, and said housing being adapted to receive the cushioning element of the draft gear longitudinally of the yoke through the hooded end thereof.

A further feature of the invention is to provide in combination with center sills and front and rear stop members, a hooded yoke preferably of the vertical type and having an integral draft gear housing at the rear end thereof, the forward end of said housing being formed to accommodate and cooperate with friction members suitably arranged adjacent an interposed follower.

There are other features of the invention as will more fully appear from the detailed description of the embodiment which has been chosen for the purposes of illustration when taken in connection with the accompanying drawings in which—

Figure 1 is a view in horizontal section through a portion of a railway car draft rigging showing the yoke member and integral spring housing associated with the friction draft mechanism.

Figure 2 is a central vertical sectional view on the line 2—2 of Figure 1, the housing of the yoke member being shown in side elevation.

Figure 3 is a transverse vertical sectional view on the line 3—3 of Figure 2.

Figure 4 is a detail transverse sectional view through the yoke member on the line 4—4 of Figure 2, the friction wedges being shown in elevation.

Figure 5 is a transverse sectional view on the line 5—5 of Figure 2.

Referring to the drawings in which similar reference characters designate corresponding parts in the several views, the center sills are indicated by the numeral 1, each of said sills being provided at its forward end with a slot 2. Draft stop members 3 are connected by means of rivets to the inner faces of the center sills, said stop members being provided with slots 4 designed to register with the slots 2 in the center sills and having stop faces or lug portions 5 extending inwardly of the sills, said stop lugs being suitably reinforced by longitudinally arranged ribs 6. A striking casting is shown at 7, said casting being connected to the center sills and stop members 3 by means of rivets 8.

The coupler 9, and more especially the shank thereof, is arranged for sliding engagement with the yoke member 10, a coupler key 11 extending through the slots in the center sills and slot members and constituting the connection between the coupler and yoke. The backstop member 12 is interposed between and unites the center sills, rivets 13 serving to connect the side walls of the backstop to the inner faces of said sills. A buffing face is provided on said backstop, said face being suitably reinforced by means of horizontal and vertical longitudinally extending ribs, as shown. The backstop casting is adapted to be engaged by the rear portion of the movable yoke member on buffing movement, as will be understood.

The yoke member 10 is preferably of the vertical type, and is formed with a hooded head or end 14, the opposite side walls of which are slotted, as at 15, to receive the coupler key 11. The outer ends of the side walls are of greater cross sectional area, thereby providing an increased bearing surface for the key, the said side walls being also outwardly flared with their outer faces arranged in relatively close spaced relation to the inner faces of the center sills.

An integral housing or casing 16 is

formed on the rear portion of the yoke member, said housing being closed at its rear end by a wall 17 and open at its forward end to receive the cushioning element of the draft rigging. Formed within the housing is the spring pocket or recess into which is inserted through the front end of the yoke, the cushioning element of the draft rigging. The forward end of the housing is provided with horizontally flared wall portions 18, each of which is formed with an inwardly inclined friction wedge face 19, the outer ends of the flaring portions 18 being relatively closely spaced from the inner faces of the center sills.

Intermediate the wedging friction faces 19 I provide a plurality of friction blocks 20 and a wedge 21. The friction blocks 20 are adapted respectively to engage the friction faces 19 of the housing and the wedge 21 is interposed between the wedging friction faces 22 of the blocks. The friction blocks are effectively retained in position by the upper and lower wall portions of the yoke.

Seated against the inner end of the wedge member 21 is a cushioning spring 23 of the draft rigging, and if desired there may be provided an additional lighter spring 24 interposed between the rear wall 17 of the housing and a recess 25 provided in the wedge member 21. The springs are completely encased within the housing forming the rear end of the yoke. A screw-threaded opening 26 is provided in the wedge 21, said opening being adapted to receive the threaded end of a member inserted through an aligned opening in the wall 17 of the housing, to facilitate the shipping and handling of the parts prior to their assembly for use, as will be understood.

The follower is interposed between the friction blocks 20 and the draft stop lugs, said follower being adapted to transmit the buffing strains from the coupler to the cushioning element and backstop, and also serving to transmit the pulling strains to the draft lug members upon the forward movement of the yoke member, as will be understood. Buffing loads in excess of the cushioning element are transmitted through the follower contacting with the forward edges of the flaring portions 18 and thence through the housing 16 to the backstop, said housing

forming a maximum column area through which the strains are imparted to the rear stop member and center sills. The spring housing 16 is preferably rectangular in cross section to provide this increased or maximum area.

A yoke supporting member 28 connected to the lower flanges of the center sills provides a guide and support for the rear end of the yoke or housing, as shown. Upstanding portions 29 are formed on said supporting member between which the housing is guided, as clearly shown in Figure 5. The top guide and retaining member 30 is arranged above the housing, said member bridging and being connected to the center sills. The usual cover plate is indicated at 31.

A draft rigging constructed in accordance with my present invention provides a simple, compact and easily assembled structure wherein the cushioning spring can be readily inserted from the front end of the housing and effectively retained therein by the interposed friction blocks and follower, which latter are supported by the yoke member. Other advantages in disassembling are also obvious from the use of the unitary member serving as the draft yoke and spring barrel. Changes commensurate with the scope of my invention may be made and the terms herein are to be taken in their descriptive and not in their limiting sense.

I claim:

In a draft rigging, the combination with a coupler, of a rectangular casing or yoke member cooperating therewith, said casing having portions of its side walls removed intermediate the ends thereof, other and corresponding portions of each of said side walls being arranged at an angle to the longitudinal axis of said casing, friction elements and a spring within said casing, some of said elements coating with the angular portion of said side walls, and a follower extending transversely through said casing, and means extending through the side walls of said casing adjacent the ends thereof for operatively connecting said coupler and casing.

In testimony whereof I affix my signature.

BYERS W. KADEL.
